UNITED STATES PATENT OFFICE.

RUDOLF EICHENBERGER, OF ZURICH, SWITZERLAND.

PROCESS AND DEVICE FOR PRODUCING PERMANENT WAVES IN THE HAIR.

Application filed December 11, 1925, Serial No. 74,873, and in Switzerland December 12, 1924.

It is already known to curl the hair by the action of the heat of electrically heated curling sticks, i. e. by interior heating. These devices are, however, not suitable for 5 producing the so-called permanent waves façon Marcel, as the latter require a simultaneous steaming and heating of the hair. The production of permanent waves per se is not novel, it has heretofore been proposed to produce these waves by means of 10 an impracticable heater, which exteriorly surrounded the strand of hair wound spirally around a blank stick and wrapped by a piece of flannel saturated with a liquid.

15 According to the present process the permanent waves are produced with the aid of an electrically heated winding stick by covering the internally heated winding stick at first with a layer adapted to be 20 saturated with a liquid and to prevent an over-heating of the hair, whereupon the layer is saturated and a strand of hair is wound cross-wise (in the shape of an 8) on this layer and the wound strand of hair 25 is covered by a layer of material that is impervious to moisture so that when the electric current is supplied the electric heating causes the liquid contained in the first 30 layer to evaporate and the vapours are prevented to escape by the second layer and are caused to act on the strand of hair during a prolonged period.

The accompanying drawings serve to explain the process and the device according 35 to the present invention. In the drawings:

Fig. 1 shows in a longitudinal section a constructional example of the winding stick,

Fig. 2 is a view of the winding stick drawn to a smaller scale,

40 Fig. 3 shows the stick wrapped in a first layer adapted to be readily saturated,

Fig. 4 shows the wrapped stick on which a strand of hair is being wound cross-wise,

45 Fig. 5 shows the wrapped stick onto which a strand of hair has been wound covered by a layer of material that is impervious to moisture,

Fig. 6 shows the product of Fig. 5 wrapped in a second layer that is impervious 50 to moisture and retains the vapors, and means provided to heat the whole,

Fig. 7 shows in a smaller scale one of the layers applied according to Figs. 5 and 6 developed in a plane,

55 Fig. 8 shows a plait of hair on which per-

manent waves have been produced by the present process, and

Fig. 9 shows diagrammatically cross-windings.

The winding stick comprises a core 1 of 60 insulating material, for instance of porcelain, around which the heating wire 2 is wound so that the ends of the wire 2 are situated at the ends of the core 1 made of porcelain or of another heat resisting insulating material and are connected to pins 3 cooperating with connecting plugs 4. The feature that the wire passes only in one direction through the stick and does not return to the same end permits to produce a thin stick. Around the wound wire 25 70 a layer 5 of an insulating material, for instance of mica, is arranged and the whole is inserted in a metal sleeve 6, provided at its ends with insulating plugs 7 cemented 75 to it, the connecting plugs 3 passing through said insulating plugs 7. In this manner a thin winding stick may be obtained.

In order to produce permanent waves with the stick the latter is at first covered by a 80 damp layer 8, for instance a piece of flannel wrapped around the stick as is shown in Fig. 3, and saturated with a liquid, thereupon a strand of hair 9 is cross-wise wound upon the stick in the manner diagrammatically illustrated in Fig. 9 so that the parts of the strand cross each other at 10 (Fig. 4). The first layer 8 serves not only the purpose of taking up i. e. liquid to be saturated with liquid but it also acts as a heat insulator for 90

the hair as the stick gets hot and the hair might otherwise be singed. Thereupon a cover 11 of parchment paper is wrapped around the product according to Fig. 4, the paper being provided with notches 12 to permit it being placed in position, and taking into account that the part 13 of the strand of hair is fixed to the head. This cover forms a layer which is impervious to moisture so that the vapors which are formed 100

later on by the heating action are retained to act upon the hair during a certain time. Around the layer 11 another layer 14 of a material that is impervious to moisture and that retains vapors, for instance a layer of a pliable metal foil, is wrapped. Experiments have shown that the wrapper of parchment paper may also be omitted. Thereafter the conduits 15 fixed to the contact plugs 4 are connected to a current supply and the permanent waves are produced.

uent waves shown in Fig. 8 are obtained by the combined action of the warm dampness and of the heat.

The saturation of the wrapper 8 may be effected with any impregnating liquid.

I claim:

1. A process for producing permanent waves in the hair by utilizing an electrically heatable winding stick which comprises covering the winding stick with a layer adapted to be saturated with a liquid and to prevent an overheating, saturating said layer with a liquid, cross-winding a strand of hair on said saturated layer, covering said cross-
15 wound strand of hair with a layer of a material that is impervious to moisture, wrapping a metal foil upon said last mentioned layer, and electrically heating said winding stick, whereby the liquid contained in the
20 first layer evaporates and the vapors are retained for a prolonged time to act on the hair.

2. A device for producing permanent

waves in the hair, comprising a thin smooth winding stick, means to electrically and internally heat said winding stick, a first layer of a hygroscopic and heat insulating material covering said winding stick, and a second layer of a material that is impervious to moisture covering a strand of hair wound ²⁵ cross-wise upon said first layer.

3. A device for producing permanent waves in the hair, comprising a thin smooth winding stick, means to electrically and internally heat said winding stick, a first layer ³⁰ of a hygroscopic and heat insulating material covering said winding stick, a second layer of a material that is impervious to moisture covering a strand of hair wound cross-wise upon said first layer, and a third ³⁵ layer of a metal foil covering said second layer.

In testimony whereof, I have signed my name to this specification.

RUDOLF EICHENBERGER.
